UNITED STATES PATENT OFFICE.

FRANK B. RAE, OF DETROIT, MICHIGAN.

MACHINE-BRAKE.

No. 841,441.

Specification of Letters Patent.

Patented Jan. 15, 1907.

Application filed February 24, 1906. Serial No. 302,676.

To all whom it may concern:

Be it known that I, FRANK B. RAE, a citizen of the United States, residing at Detroit, in the county of Wayne and State of Michigan, have invented certain new and useful improvements in Machine-Brakes, of which the following is a full, clear, and exact specification.

This invention relates to machine-brakes such as are used on vehicles or elevators, and more especially relates to brakes wherein the initial application is controlled manually and the momentum or speed of the part which is to be retarded utilized to produce further retarding force, together with brake-applying means securing an increased power by means of cams or levers.

A further object of my invention contemplates the use of an electromagnet or other device to actuate a yielding clutch for securing the initial application of the brake, together with means for graduating the force thereof, to thereby determine the extent to which the momentum of the machine will act to further apply the brake. When using the magnet for applying the brake, I may employ the Foucault currents generated by a part moving in the magnetic field to increase the retarding force in addition to the mechanical connections acting directly on the brake itself when the magnet is energized.

This invention also comprises improvements in the mechanical construction and arrangements of parts whereby a powerful and compact mechanism is produced which is not liable to disarrangement and failure in practical use.

In the accompanying drawings, Figure 1 represents in elevation one form of my invention, showing a band-brake. Fig. 2 is a longitudinal section. Fig. 3 is a view similar to Fig. 1 of another form of my invention with provision for utilizing the drag produced by the Foucault currents generated by the rotation of the magnet relatively to the part to be braked. Fig. 4 is a longitudinal section. Fig. 5 is an elevation of a further modification. Fig. 6 is a longitudinal section. Fig. 7 is a longitudinal section of another form of my invention, and Fig. 8 is a cross-section.

1 is the shaft of a machine or an axle, to which is attached the brake drum or wheel 2, having a projecting rim 3. Upon the inner hub of the wheel 2 is mounted the electro-magnet-cores 4 4 and magnet-windings 19 19, the magnet-cores being integral with the ring

extensions 5 5, which extensions are hinged together at 6. Projections of this ring 7 7 are held together by the spring 8. The entire magnet system, its supporting-ring, and retaining-spring is thus free to revolve around the hub projection 21 of frame-support 14. Also carried by ring 5 and forming a part of this ring is the sprocket 9, and engaging with the sprocket is the sprocket-chain 10. The center of the chain 10 passes around an arc of the sprocket 9, and its ends are attached to the rocker-arm 11 by the pivot connections 12 12. The rocker-arm 11 is pivoted at 13 upon the stationary supporting-frame 14, and attached to the rocker-arm is the lug 15, having studs 16 16, to which is attached one end of the resetting-spring 18, the other end of which is attached to the magnet-ring 5 at its center pivot 6.

The operation of the device shown in Figs. 1 and 2 is as follows: Upon current being caused to pass through the windings 19 19 the cores 4 4 are energized and attracted outwardly toward the inside of rim 3 of the drum or wheel 2. This expansion takes place against the spring 8, and the resulting friction between the pole-faces 20 20 and the rim 3 is in proportion to the current strength in the windings 19 19 and resultant strength of the magnet-cores 4 4. The friction so produced between the pole-faces 20 20 and the rim 3 of the wheel 2 causes the magnetic system, its supporting-ring 5, and the sprocket 9 to be rotated around the projection or hub 21 of the frame 14 in the direction of travel of the wheel 2. The chain 10 will then pull one end of the lever 11 downward, thereby moving the take-up lug 15 and connection 16 to decrease the diameter of the brake-strap with relation to the diameter of wheel 2, causing a frictional braking force to be applied to the outside of the rim 3 of the wheel 2 or other moving parts. There are thus two forces used to retard the wheel 2, the friction on the inside of rim 3 of the pole-faces 20 20 depending upon the strength of the magnet and the friction of the band 17 on the outside of rim 3. It will be seen that the lever system, together with the drag of the magnets on rim 3, tends to increase the force with which the brake is applied to the outside of the rim.

Inasmuch as the magnets will have an arc of oscillation around shaft 1 only so far as is permitted to apply the brake with the requisite force, the magnet-circuit connections

may be easily made so as to be controlled from a distance by the operator. In the case of a vehicle, for instance, a switch in the magnet-circuit will be located so as to be controlled by the operator and the current may be supplied from a storage battery. With electric vehicles the same source of current which supplies the motors may be used.

The magnet-controlling circuits may be arranged in any suitable manner and are not therefore illustrated herein. It is also noted that the initial braking force applied by the magnets 4^a and windings 19^a may be made greater or less at will by increasing or decreasing the current strength, thus altering the magnetic drag of the magnets. The increasing braking force applied by the levers to the brake strap or shoe is thus controllable and may be varied through a wide range of applied frictional or retarding pressure.

Figs. 3 and 4 show another form of my invention embodying the same general principles of operation, except that in this form provision is made for more efficiently utilizing the Foucault currents produced whenever there is movement of a conductor in a magnetic field. In this construction the magnet 19^a is of the iron-clad type, in which the coil 19 surrounds an inner core 19^b and is surrounded by the outer shell 4^a, the whole being rotatably mounted on a hub 21 and carrying a sprocket 9 for actuating the brake-lever 11^a, as before. The poles 4^a and 19^b will be of opposite polarities and are extended outward, as shown, so as to form a polar space in the strong magnetic field of which fluted extension 3^b of drum 3^a revolves. When the magnet is energized, the rotation of drum 3^a in the magnetic field will produce a drag tending to rotate the magnet itself on bearing 21, and thus apply the brake. The brake-applying connections differ specifically from those shown in Figs. 1 and 2 in that the lever on 11^a carries rollers 22, which apply the brake-shoes 17^a to rim 3^a through a cam-lever 23. The lever 23 is connected with brake-shoe arm 25 by pin 24, and 18^a is a releasing-spring for spreading the brake-shoe arms 25, both of the latter being pivoted on shaft 13. The cam-lever is connected with the other brake-shoe arm 25 by a rod 25^a, so that any movement of lever 23 by rollers 22 applies the brake-shoes 17^a, mounted on arms 25, to rim 3^a. The magnetic drag thus produces the initial application, and its intensity depends upon the speed of rotation, intensified by the increased leverage.

In Figs. 5 and 6 I show a further modification of my invention, in which the magnetic core 4^a 19^b and its coil 19^a are mounted upon a hub extension 26^a of the stationary frame 14, the magnet rotating on the roller-bearings 26. In the operation of this device the magnet-coil 19^a is energized to produce the

magnetic poles N and S, as before, which magnetization, acting upon the arm 3^b of the brake-wheel 3^a and augmented by the Foucault currents, as before described, operates to produce a magnetic drag between the magnet system and the rim 3^a. In this construction there is attached to the magnet system at 27 a ring 28, partially surrounding the drum 3^a, and mounted upon this ring at diametrically opposite points horizontally are the rollers 29 29, which are free to revolve upon the pivots 30 30. These wheels engage upon a cam 31, attached to the brake-arms 25^b 25^a, upon which arms are mounted the shoes for producing the braking friction 80 upon the outside of the drum 3^a.

The operation of this modified device is as follows: The magnetic drag produced by energizing the coil 19^a, acting upon the rim 3^b of wheel 3^a, causes the magnetic system to be revolved, carrying with it the ring 28 and rollers 29. The rollers bearing upon the cam 31 thereby force the arms 25^b 25^a and their attached brake-shoes against the outer rim of the drum 3^a, applying a braking force 90 through the leverage of the cam 31. Upon demagnetizing the core 19^a 19^b the pull between this core and the rim 3^b is released, allowing the spring 18^a to expand to force the arms 25^a and the attached brake-shoes 95 away from the outer surface of the drum 3^a, and at the same time the reaction of one of the springs 32 32, attached by the flexible connection 33 33 to the magnet 4^a, returns the magnet system to its normal position. At the same time the ring 28 and wheels 29 return to horizontal position, thereby releasing the pressure between the wheels 30 and the cam 31 to enable the spring 18^a to spread the brake-shoes. The combined action of the springs 32 and 18^a thus restores the entire braking system to its normal position.

Referring to Figs. 7 and 8, the machine-shaft 1 carries the brake-drum 3^a similarly to the constructions before described, the flutings 3^b being in this form on the inner periphery of the drum 3^a. The magnet-coils 19^a are wound in a groove 35 of magnet-core 19^b, which latter is mounted to oscillate on a fixed stud 37, carried by the framework. The magnet-core or part attached thereto carries cam-shaped projections 38, which when oscillated by the magnet spreads the brake-shoes 39, pivoted on stud 40, against the inside of drum 3^a, thus applying the brake. 41 is a retracting leaf or coil spring attached to the brake-shoes 39 and returning the parts to normal position when the magnetic drag is relieved. In this form it will be seen that a very slight movement of the cams 38 produces a considerable movement of the brake-shoes and also that a substantially closed magnetic circuit is provided as in the other forms described.

While I have illustrated and explained the

operation of my invention applied to mechanism to which magnetization is applied as the initial retarding and braking force to secure the final braking effort, it will be understood that this initial application may be produced by the employment of other forces whereby the revolution of the wheel or drum is caused to apply the final braking effort to mechanical connection which increases the effective force of application, and my invention will be especially advantageous where applied to high-speed shafts, inasmuch as the higher the speed the greater the drag that will be produced both by the induced currents and by the mechanical connections between the parts. It will be plain that other manually-controlled means could be used to effect the initial pressure in place of the magnet system shown or that various other systems of cams or levers could be readily arranged to accomplish the same result.

I do not, therefore, limit myself to the means illustrated for producing the initial braking pressure or to the means for transmitting such initial pressure to the wheel or drum which is to be retarded.

Having thus described my invention, I declare that what I claim, and desire to secure by Letters Patent, is—

30 1. In a brake system, the combination with a revolute driven member, of electromagnetic means for retarding said member and mechanical means actuated by said electromagnetic means, substantially as described.

2. In a brake system, the combination with a revolute driven member, of a mechanical and an electromagnetic means for retarding the movement of said member, said 40 mechanical means acting with an intensity proportional to that of the electromagnetic means, substantially as described.

3. In a brake system, the combination with a revolute driven member, of a mechanical and an electromagnetic means for retarding the rotation of said member, and an intermediate mechanical connection by which said electromagnetic means actuates said mechanical means at a greater power, 50 substantially as described.

4. In a brake system, the combination with a revolute driven member, of an independently-movable member, means for causing said members to react electromagnetically upon each other whereby to drag said movable member with said revolute member, and a brake mechanism actuated by said movable member, substantially as described.

5. In a brake system, the combination 55 with a revolute driven member, of an independently-movable member, a mechanical brake for said driven member actuated by a rotation of said independently-movable member, and electromagnetic means for causing said members to move simultaneously, where-

by said driven member is retarded in proportion to the drag between it and the other member, substantially as described.

6. In a brake system, the combination 70 with a revolute driven member, of a member independently movable about the same axis, and a mechanical brake for said driven member actuated by the rotation of said independently-movable member, means for producing a yielding magnetic drag between said members, and actuating connections for applying the brake, substantially as described.

7. In a brake system, the combination 75 with a revolute driven member, of a brake therefor, a brake-actuating member mounted to oscillate relatively to said driven member, magnetic means for yieldingly connecting said members, and brake connections controlled by the oscillation of said brake-actuating member, substantially as described.

8. In a brake system, the combination 80 with a revolute driven member, of a brake therefor, a brake-actuating member mounted to oscillate relatively to said driven member, 90 magnetic means for yieldingly connecting said members, brake connections controlled by said oscillation of said brake-actuating member, and means for restoring said parts to release said brake, substantially as described.

9. In a brake system, the combination 95 with a revolute driven member, of a brake therefor, a brake-actuating member carrying an electromagnet mounted to oscillate relatively to said driven member, means for energizing said magnet to oscillate said member, and brake-actuating connections controlled thereby, substantially as described.

10. In a brake system, the combination 100 with a revolute driven member, of a brake therefor, a brake-actuating member having an electromagnet mounted thereon with projecting pole-pieces, an extension on said driven member adapted to rotate adjacent 110 said pole-pieces, actuating connections for the brake, and means for producing an electromagnetic drag between said driven member and the brake-actuating member to apply the brake, substantially as described.

11. In a brake system, the combination 115 with a revolute driven member, of a brake therefor, a brake-actuating member having an iron-clad electromagnet mounted thereon with projecting pole-pieces, an extension on 120 said driven member adapted to rotate adjacent said pole-pieces, actuating connections for the brake, and means for producing an electromagnetic drag between said driven member and the brake-actuating member to apply the brake, substantially as described.

12. In a brake system, the combination 125 with a revolute driven member, of a brake therefor, a part mounted on the framework so as to oscillate in either direction from a central 130

position to apply the brake, a spring for restoring said part to central position, and an electromagnet for moving said part, substantially as described.

13. In a brake system, the combination with a revolvable driven member, of a brake therefor, a part mounted on the framework so as to oscillate in either direction from a central position to apply the brake, a spring for restoring said part to central position, and an electromagnet adapted to be oscillated by said driven member for moving said part, substantially as described.

14. In a brake system, the combination with a driven member, of a brake mechanism, mechanical connections for actuating said brake, and electromagnetic means acting on said driven member to retard the same, and connections whereby the said connections are actuated by said electromagnetic means, substantially as described.

15. In a brake system, the combination

with a driven member, of a brake mechanism, a means for actuating said brake, a rotatable electromagnetically-actuated member, and actuating connections between said member and said means, effective upon rotation of said member, substantially as described. 25

16. In a brake system, the combination with a driven member, of a brake mechanism, means for actuating said brake, a rotatable electromagnetically-actuated member, and cam-actuating connections between said member and said means, and effective upon rotation of said member, substantially as described. 30 35

In testimony whereof I affix my signature in presence of two witnesses.

FRANK B. RAE.
